UNITED STATES PATENT OFFICE.

HARRY L. FEASEL, OF NEW YORK, N. Y.

MOP.

1,283,404.

Specification of Letters Patent. Patented Oct. 29, 1918.

Application filed June 19, 1914. Serial No. 846,007.

To all whom it may concern:

Be it known that I, HARRY L. FEASEL, a citizen of the United States, residing at New York, in the county of New York and State 5 of New York, have invented new and useful Improvements in Mops, of which the following is a specification.

This invention relates to that class of mops commonly known as "dustless mops", al- 10 though not limited thereto.

One of the objects of the invention is to provide a mop head of skeleton form, and simple and inexpensive in construction, and of a material that will not be readily at- 15 tacked by water or other fluids with which it will come in contact while in use. A further object is to provide a mop head to which the mop fabric may be readily at- tached, and easily detached for cleansing or 20 renewal. A further object is to provide means whereby accidental disengagement of the mop fabric from the mop head is prevented without the use of catches, or the like.

25 The invention will be hereinafter fully set forth and particularly pointed out in the claims.

In the accompanying drawings:—

Figure 1 is a perspective view of the mop 30 head with the mop fabric detached. Fig. 2 is a plan view showing the arms separated. Fig. 3 is a plan view with the mop fabric secured in position. Fig. 4 is a rear view of the complete mop. Fig. 5 is a plan view of 35 a slightly modified form of mop head.

Referring to the drawing, the mop head comprises two plate like sections 10, 10^a, slideable one upon the other and pivotally connected by a pivot pin 11. Complemental 40 abutments 12 are provided to limit the pivotal movement of said sections. The section 10 is provided with a diagonally disposed boss 13 which coincides with a diagonal opening 13^x in section 10^a when the sections 45 are in closed position. The boss 13 and opening 13^x are threaded as indicated at 15. Extending laterally from the respective sections 10, 10^a are arms 16 which are curved or bent at 17 to form arms 18. The arms 18 con- 50 verge from the bends 17, and are separated at their extremities by a space 19. It will be noted that the arms 16 may be relatively wide at the point where they join the members 10, 10^a, and tapering toward the bends 17 and from said bends the arms 18 gradu- 55 ally taper to their extremities. In this manner the arms are made sufficiently strong to withstand any strains to which they may be subjected when in use, and at the same time the arms 18 are rendered sufficiently resili- 60 ent to retain the mop material in position when the abutments 12 are in contact. A handle or water pipe 20, as the case may be, having proper screw threads may be made to engage the threads 15, to lock the mem- 65 bers 10, 10^a in closed relation.

The mop fabric comprises the fibrous material 21 secured within a flexible tubular binding 22, of suitable material, such as canvas or other similar fabric. The mop fabric 70 is made flexible so that it will assume any desired shape in plan view, the shape being controlled by the shape of the mop head.

In practice, when it is desired to use my improved mop, handle 20 is disengaged from 75 sections 10, 10^a whereupon the said sections may swing on pivot 11, permitting a relative movement of the arms 18. The ends of the said arms 18 are then passed into the open ends of the tubular binding 22, and the 80 said binding is worked backward or threaded over said arms 18, around the bends 17 and over the arms 16 until the ends of the binding are forced against the members 10, 10^a. Said members are then brought into 85 closed position and locked by handle 20. The mop fabric is thus caused to assume a triangular shape in plan view, whereby it may be conveniently worked into corners while in use. The friction of the binding 90 against the arms of the mop head and the resilience of the arms 18 all tend to retain the mop fabric in position upon the head and to prevent relative slipping. When it is desired to remove the mop fabric from the 95 head, the boss is held in one hand and a finger of the other hand is hooked inside of the binding opposite the opening or space 19. A straight pull will then effect the withdrawal of the mop fabric. If desired, water 100 may be supplied through the hollow handle 20 by attaching said handle to a suitable source of water supply.

If desired the mop head may be made in one piece as indicated in Fig. 5. In this form 105 the arms 16^a and 18^a are rigidly secured to a boss 13^a, the arms 16^a extending laterally from said boss and joining the arms 18^a by the bends 17^a. In practice the arms 18^a are ex- 110 tended into the open ends of the mop bind-

ing 22 and the latter passed around the bends 17^a into contact with the boss. The mop fabric is removed in the same manner as that described in connection with the first mentioned form of my invention.

Having thus explained the nature of my invention and described an operative manner of constructing and using the same, although without attempting to set forth all 10 of the forms in which it may be made, or all of the forms of its use, what I claim is:—

1. A triangular mop-head comprising a straight side, a handle socket in the middle of said straight side and members forwardly 15 converging in front of said handle socket, said members forming the other two sides of the triangle and having an opening between the ends through which the mop fabric may be applied to said head.

2. A mop head comprising a handle-engaging portion having laterally projecting arms provided with integral forwardly projecting converging arms separated at their 20 forward ends, said arms gradually diminishing in thickness from the handle engaging portion to the extremities.

3. A mop head comprising a handle-engaging portion formed of articulated sections having laterally projecting members 25 provided with forwardly projecting converging arms.

4. A mop head comprising a handle-engaging portion formed of articulated sections having laterally projecting members 35 provided with forwardly projecting converging arms, said sections having complementary abutments to limit closing movement thereof.

5. A mop head comprising a handle-engaging portion formed of articulated sections having laterally projecting members provided with forwardly projecting converging arms, said sections having coinciding 40 openings, and a handle engaging said 45 openings.

6. The combination with a mop having a tubular binding, of a mop head provided with forwardly projecting converging arms separated at their ends and extending longi-

tudinally into the ends of said binding, a 50 portion of said binding spanning the space between said separated ends.

7. The combination with a mop head comprising a handle-engaging portion having laterally extended arms provided with integral forwardly projecting converging arms separated at their forward ends, of a 55 mop having a tubular binding threaded over said arms and having its ends in contact with said handle-engaging portion, a portion of said binding spanning the space between said separated ends.

8. In a device of the class described, a 60 mop-holder and former comprising a rim formed with a gap providing separated ends 65 for threading into a mop band, and a handle member supported by a portion of the rim leaving the gap open for threading the mop band on to the rim and toward said member, and a mop fabric on said holder and bridging said gap.

9. In a mop, an absorbent mop fabric 70 having a tubular portion, and a pair of arms extending into the ends and supporting the mop fabric, each arm having a free end 75 in proximity to and permanently spaced from the free end of the other arm to permit the tubular portion of the mop fabric to be slipped upon said arms to be supported thereby.

10. In a mop, an absorbent mop fabric having a tubular portion, a pair of arms joined at one end and extending at first 80 away from and then toward each other, the opposite free ends of the arms being in 85 proximity to and spaced from each other and extending into the ends of the tubular portion of the mop fabric which extends across the opening between the ends of the arm, and a handle secured to the arms 90 where they join each other.

In testimony whereof I have hereunto set my hand in presence of two subscribing witnesses.

HARRY L. FEASEL.
